UNITED STATES PATENT OFFICE.

JOHN A. CHAMBERS, OF NEWBERG, MISSOURI.

MAIL-RECEIVING DEVICE.

1,372,602.

Specification of Letters Patent. Patented Mar. 22, 1921.

Application filed June 10, 1920. Serial No. 387,922.

To all whom it may concern:

Be it known that I, JOHN A. CHAMBERS, a citizen of the United States, residing at Newberg, in the county of Phelps and State 5 of Missouri, have invented a new and useful Mail-Receiving Device, of which the following is a specification.

It is the object of this invention to provide novel means whereby mail bags and the 10 like may be caught and delivered into a moving train. The invention contemplates the provision of novel means for mounting the catcher on the car and for holding the catcher in adjusted positions.

15 Another object of the invention is to provide novel means for holding the bag after the bag has moved within the car.

It is within the province of the disclosure to improve generally and to enhance 20 the utility of devices of that type to which the invention appertains.

With the above and other objects in view, which will appear as the description proceeds, the invention resides in the combination 25 and arrangement of parts and in the details of construction hereinafter described and claimed, it being understood that, within the scope of what is claimed, changes in the precise embodiment of the invention 30 shown can be made without departing from the spirit of the invention.

In the accompanying drawings:—

Figure 1 shows in horizontal section, a portion of a car whereunto the device forming 35 the subject matter of this application has been applied, the view being, in substance, a top plan; Fig. 2 is an elevation of the structure shown in Fig. 1; Fig. 3 is a section taken approximately on the line 3—3 40 of Fig. 2; and Fig. 4 is a section taken approximately on the line 4—4 of Fig. 1.

The numeral 1 denotes a car, the side wall of which is provided with a door way defined by jambs 3 and 4. A plate 5 is secured 45 to the side wall of the car 1, adjacent to the jamb 3. An arcuate guide 6 is attached as shown at 7 to the plate 5 and is provided with a resilient extension 8 prolonged inwardly into the car 1 through the door way 2. A base block 9 is secured to the side wall of the car 1 adjacent to the jamb 4, the block 9 being supplied in its outer surface with recesses 10, shown best 50 in Fig. 3, and defining shoulders in the block. Bearings 11 are mounted on the block 9, and in the bearings 11, a shaft 12,

constituting a part of a catcher 14, is mounted to rock. The shaft 12 is provided with projections 15 which enter the recesses 10, when the catcher 14 is swung downwardly 60 into the horizontal position depicted in Figs. 1 and 3 of the drawings. The recesses 10 and the projections 15 constitute coöperating elements, limiting the downward swinging movement of the catcher 14 to a horizontal position. The shaft 12 of the catcher 14 is equipped with a handle 16 extended inwardly through the door way 2 of the car 1 when the catcher is in a horizontal position. The numeral 17 denotes a sustaining 65 member, preferably in the form of a resilient strip, secured at its lower end to the jamb 4, and outwardly inclined intermediate its ends, as shown at 25. When the catcher 14 is in a horizontal position, the 70 upper end of the sustaining member 17 engages beneath the handle 16 and prevents the catcher from folding upwardly against the side wall of the car. The sustaining element 17 may, however, be disengaged 75 from beneath the handle 16 and then, through the instrumentality of the handle, the catcher 14 may be swung upwardly into a vertical position, as indicated in dotted line in Fig. 2 of the drawings. When the 80 catcher 14 is swung upwardly as aforesaid, the sustaining member 17 extends longitudinally of the handle 16 and engages behind the same, to hold the catcher upturned. Since the sustaining member 17 is inclined 85 as shown at 25, the handle 16 will spring the member 17 inwardly, when the catcher is swung from the dotted line position of Fig. 2 to the solid line position of Fig. 1, the member 17 engaging automatically beneath 90 the handle 16, as delineated in Fig. 1.

The catcher 14 comprises an outer bar 18 provided at its rear end with an inwardly projecting extension 19 secured to the shaft 12, the shaft 12 being equipped at its forward end with an outwardly projecting extension 20 secured to the bar 18. The forward end of the bar 18 merges into an arm 21 disposed at an acute angle to the bar 18, the arm curving to form a prolongation 100 105 projecting into the car 1, through the door way 2. The part 30 of the arm 21 is supplied with a transverse fork 22 in which the spring extension of the guide 6 is received. The arm 21 is connected to the bar 18 by a 110 strut 23, a diagonal brace 24 joining the arm and the bar, between the parts 20 and 23.

The way in which the catcher 14 is swung upwardly and downwardly, has been set forth hereinbefore. The mail bags or other articles pass between the arm 21 and the 5 guide 6 and move inwardly, within the car 1, through the door way between the elements 30 and 8. The fork 22 serves as a stop, limiting the inward movement of the mail bag. The extension 8 may at any time 10 be sprung out of the fork 22 whereupon the mail bag will drop to the floor of the car.

Having thus described the invention, what is claimed is:—

- 15 1. In a device of the class described, a car having a doorway; a catcher extended transversely of the doorway and including a shaft journaled on the car, the shaft and the car having interengaging elements coöperating to hold the catcher in an approximately horizontal position when the catcher is swung downwardly; a handle on the shaft and extending into the doorway when the catcher is in an approximately horizontal position; and a spring sustaining element 20 mounted on the car, the sustaining element 25

engaging releasably beneath the handle to prevent the catcher from swinging upwardly when the catcher is in an approximately horizontal position, the sustaining element engaging behind the handle to prevent the catcher from swinging downwardly when the catcher is turned upwardly into an approximately vertical position. 30

2. In a device of the class described, a car having a doorway defined by jambs; a guide 35 secured to one jamb and comprising a resilient extension projecting into the doorway; and a catcher mounted to rock on the car adjacent to the other jamb, the catcher comprising an arm disposed approximately parallel to the guide and its extension, the arm having a transverse element wherewith the extension is detachably engaged. 40

In testimony that I claim the foregoing as my own, I have hereto affixed my signature in the presence of two witnesses.

JOHN A. CHAMBERS.
